UNITED STATES PATENT OFFICE.

ELIJAH CURTIS CLARK AND ALVAH DEWEY, OF CANNELTON, INDIANA.

FEED MECHANISM FOR GRINDING-MILLS.

SPECIFICATION forming part of Letters Patent No. 291,031, dated January 1, 1884.

Application filed August 30, 1883. (No model.)

To all whom it may concern:

Be it known that we, E. C. CLARK and ALVAH DEWEY, of Cannelton, in the county of Perry and State of Indiana, have invented 5 certain Improvements in Feed Mechanism for Grinding-Mills, of which the following is a specification.

Our invention relates to an automatic feed-controlling mechanism for roller-mills, where- 10 in the weight of the grain or other material in the feed-hopper is applied, through intermediate devices, to open the feed-gate, which latter is automatically closed when the supply of grain is exhausted.

15 The invention consists in the peculiar combination and arrangement of parts hereinafter explained in detail and claimed.

Referring to the accompanying drawings, Figure 1 represents a side elevation of a dou- 20 ble grinding-mill provided with our improve- ments, one side of the mill being represented in vertical section through the center. Fig. 2 represents an end elevation.

It is to be understood that while we have 25 represented in the drawings a double mill, or mill containing two pair of rolls, the invention may be applied with equal facility to those mills which contain but a single pair of rolls, the feed mechanism being applied to each 30 pair independently.

Referring to the drawings, A represents the frame or body of the mill; B B, the grinding-rolls, arranged in pairs; C, the feed-rolls, arranged one above each pair of grinding- 35 rolls, and D D two hoppers arranged above the feed-rolls, each hopper having a narrow throat or outlet extending lengthwise above the surface of the feed-roll, for the purpose of delivering grain or other material thereon.

40 The foregoing parts may be constructed in any ordinary or approved manner, our invention having no special reference thereto.

In applying our improvement, we place in 45 the bottom of each hopper a board, E, hing- ing the same at the point a in such manner that its free edge, being the one nearest the outlet-throat, may rise and fall. To the free edge of this board we secure a flexible sheet, F, which is preferably crimped in a zigzag 50 form, after the manner of a bellows-body, and

secure its lower edge to the bottom of the hopper, this sheet serving to prevent the ma- terial from passing beneath the board E, leav- ing the board, consequently, free to rise and fall at all times.

55

For the purpose of controlling the dis- charge of the material through the throat of the hopper, we provide the latter with a vertically-sliding gate, G, having on its outer side a stud or pin, which is extended through 60 a narrow slit, b, to the outside of the hopper, and there connected with a vertically-sliding plate, c, secured in suitable guides, this arrangement permitting the gate to rise and fall.

65

From the upper edge of the gate, or its guiding-strip c, we connect one end of a lever, H, pivoted centrally to a fixed support, and connect its opposite end by a cord or link, I, to the free edge of the board, the re- 70 sult of this arrangement being that whenever the hopper contains a supply of grain the board E will be depressed thereby, and the lever caused to hold the feed-gate in an open position, so that the material may pass 75 with freedom through the throat to the rolls. When, however, the hopper becomes empty, or the supply of grain is diminished, the board, relieved from the weight of the grain, permits the gate on the outside to descend. 80 A flat spring, k, secured at one end firmly to the exterior of the case, bears at its upper end on the sliding plate c of the gate.

85

For the purpose of changing the tension of the spring, a threaded rod, L, is connected centrally thereto and extended downward through a fixed arm, M, and provided with an adjusting-nut, N, on the lower end. By turning the nut, the tension of the spring may be varied, and thus the gate caused to open 90 or close with greater or less ease. By a proper regulation of the spring, the feed mechanism may be adjusted in proportion to the rate at which the material is supplied to the machine, and thus a uniform delivery of material se- 95 cured. Ordinarily, the material will be sup- plied through pipes N, entering the top of the hopper in the ordinary manner.

We are aware that feed devices operated by the weight of the grain have been con- 100

structed in a variety of forms, and we therefore lay no broad claim thereto.

Having thus described our invention, what we claim is—

5 In a feed-controlling mechanism, the hopper and the hinged board in its bottom, combined with the sliding gate, the lever, link, and sliding plate connecting the board and

gate, the external spring, and the adjusting-screw combined with said spring.
